UNITED STATES PATENT OFFICE.

CHARLES W. CROWELL, OF BISCOE, NORTH CAROLINA.

SPARK-ARRESTER.

1,229,588.

Specification of Letters Patent. Patented June 12, 1917.

Original application filed April 5, 1911, Serial No. 619,051. Divided and this application filed April 6, 1914. Serial No. 829,920. Renewed June 3, 1915. Serial No. 31,971.

To all whom it may concern:

Be it known that I, CHARLES W. CROWELL of Biscoe, in the county of Montgomery and State of North Carolina, have invented a 5 certain new and useful Improvement in Spark-Arresters, and do hereby declare that the following is a full, clear, and exact description thereof.

My invention relates to steam boilers and 10 considering it in its entirety, more particularly to locomotive steam boilers, and briefly, but not exclusively stated, my object is to arrest, or prevent the discharge of sparks and unconsumed gases or products 15 of combustion by securing the extinguishment of sparks and causing the further combustion of the incompletely consumed gases, or matters, thus economizing in, or getting a greater efficiency out of the fuel; and to 20 provide a construction which will present no high extensions or projections from the top of the boiler and thus render possible the passage of the locomotive through tunnels, under bridges or other overhead structures, which projections or extensions on 25 the top of the boiler might encounter, and to this end and to secure other advantages which will be evident when my invention is described more at large hereinafter in 30 the specification, my invention consists in the construction substantially as hereinafter specified and claimed.

The invention forming the subject hereof is illustrated as embodied in the boiler forming the subject of my application No. 619,051, filed April 5, 1911, and is divided out of that application pursuant to a requirement of the Patent Office and I, therefore, illustrate the present invention as 35 similarly embodied as in that application, but without limiting myself to its embodiment in that particular construction of boiler, or to any particular construction of boiler.

40 In the accompanying drawings—

Figure 1 is a longitudinal vertical section of such a boiler as that illustrated in my application above mentioned with my invention which forms the subject hereof 45 adapted thereto;

Fig. 2 is a front elevation thereof;

Fig. 3 is a cross section on the line 3—3 of Fig. 1, and drawn on a larger scale than the other figures.

50 A brief description of the general con-

struction of the boiler illustrated is all that is necessary herein, it being enough to explain that it comprises a fire box A having below the grate B an ashpit C with groups of fire tubes, or heating flues D that extend 60 from the firebox flue sheet forward to deliver the products of combustion to a smoke box E at the front end of the boiler and finally after they pass rearward and then again forward delivering them to a short 65 pipe, or flue 10, which opens through the top of the boiler and which alines vertically with a nozzle 11 that receives exhaust steam through an opening in the bottom of the boiler so that by means of such exhaust 70 steam there is a forced draft or blast upward through the pipe, or tube 10.

From the pipe, or tube 10, the escaping products of combustion enter the first of a series of chambers, which for convenience I 75 shall speak of collectively as the spark arrester, which extends horizontally rearward on the top of the boiler with a discharge opening, or outlet 12 on the top of the boiler at or near midlength thereof so that in reality I provide what in effect is a horizontal stack that extends rearward and has its discharge or outlet at its rear end. Besides lying on the top of the boiler said horizontal stack extends downward over each side of 80 the boiler saddle-wise so that its form, or shape in the main is that of an arc, or a truncated crescent, the horns of the crescent being cut off, or flat and not pointed as may clearly be seen by reference to Figs. 2 and 85 90 3 of the drawings. By giving the stack the saddle shape so that it extends down over the boiler on each side thereof, an ample area for the stack is provided so that there will be no back pressure in the stack which 95 might exist were its area in cross section too small. This enables the employment of my invention with very large boilers, for it gives ample area without requiring such projection of the stack above the top of 100 the boiler as would result in the stack striking bridges, tunnels, etc. The bottom plate 13 of the stack in cross section conforms to the curvature of the contiguous portion of the boiler, and, as indicated in dotted lines 105 in Fig. 1, it extends horizontally from the front and then inclines upward and rearward narrowing as it approaches the rear to form the contracted outlet, or discharge 110 12 and at its extreme rear portion it is

curved upward and reaches at its rear extremity to a level above the top sheet, or plate 14, so that in the forward travel of the locomotive (if it be a locomotive boiler) 5 air will impinge, or strike upon said curved surface, or lip and aid the draft through the stack. The top plate 14 extends preferably horizontally, and it also is curved in cross section and between it at its forward end 10 and a plate 15 which curves from a point at the front side of the pipe, or tube 10 upward and rearward, is an opening that forms an air inlet by which, when desired, a current of air may be caused to enter the 15 stack at the front thereof from the onward movement of the locomotive and thereby create or augment a draft through the stack. A valve, or damper 16 is provided in such 20 passage at the front end thereof by which said passage may be opened, or closed at will, a connecting rod 17 being provided that runs to the locomotive cab so that said damper may be manipulated to control the draft. A plate 18, which extends from the 25 damper 16 rearward provides a conduit, or passage 19 for air admitted by the opening of the damper, said plate 19 terminating substantially at midlength of the stack. The plate 15, or an extension 20 thereof, is carried downward and rearward toward the top 30 of the boiler and thus subdivides the stack into a forward compartment 21 having a contracted outlet 22 at its rear end which delivers the products of combustion into a second or intermediate chamber 23 which 35 is formed by a plate 24 that is spaced between the bottom plate 13 and the top plate 14 and at its rear end reaches the bottom plate 13 and from said second, or intermediate chamber 23 there is at its forward end 40 a discharge opening, or outlet 25 which leads into a third, or last compartment 26 which terminates in the stack outlet 12. Each of the outlets 22 and 25 may be varied in size 45 by similar adjustable plates, the outlet 22 having such a plate 27 and the outlet 25 having such a plate 28, each being secured by bolts so as to permit adjustment toward 50 and from the ends of the respective outlets and each coöperating with an opposite inclined surface so that the effect of such adjustment is to contract, or enlarge the area of the outlet. At about midlength of the intermediate compartment 23, it has in its 55 top plate 24 an opening 29 that establishes communication with the third or last stack chamber 26, such opening being controlled by a damper 30, which by means of a rod 31 that extends to the cab may be opened 60 and closed from the cab and thus communication is established between the intermediate and the third or last chamber, for the purpose of reducing the pressure in the intermediate chamber 23, if it should be excessive by opening up a passage therefrom

into the last chamber 26 other than and in addition to the passage through the outlet 25. To the pressure-receiving opening 29 a rearwardly extending conduit, or passage 32 connects with the forward end of the intermediate chamber. 70

In the bottom of the stack, just in rear of the outlet 22, from the first chamber 21, and preferably at each side of the stack, is an opening 33 from which a pipe 34 extends downward and rearward and enters at its rear end the ashpit C so that cinders, or other unconsumed matters that are heavy enough will be conveyed from the stack to the ashpit that is below the grate in the fire 80 box and either accumulated therein, or if light enough to pass upward will enter the firebox A and be subject to the heat thereof and in whole or in part consumed. Such matters as may pass to the rear of the opening 33 and which are heavy enough to fall to the bottom of the stack, will, by reason of the downward and forward inclination thereof to the opening 33 slide to the latter and thus find their way into the pipe 34 85 and will pass on to the ashpit. Each pipe 34 has near the ashpit end a damper 35. 90

The operation of my invention will be readily understood from the drawings, and description that has been given. The unconsumed and escaping products of combustion will pass from the pipe or tube 10 into the first chamber 13 and by the arched cover 15 thereof will be directed rearward and downward and pass from said chamber 95 21 into the intermediate chamber 23 and then will be directed forward and will pass therefrom through the forward outlet 25 thereof (any excess pressure being taken care of by manipulating the damper 30, as 100 has already been explained) and from the outlet 25 they will enter the forward end of the third, or last chamber and then be carried rearward and the blast with the unconsumed products of combustion reduced 105 to a minimum will finally emerge through the stack outlet 12. Inasmuch as the exhaust steam enters the pipe, or tube 10 with the escaping products of combustion and mingles therewith in said tube and also in 110 the first chamber 21, it will be seen that ample opportunity is afforded by the intimate contact of the steam for the extinguishment of any sparks. If, for any reason, it is desired to supplement the draft 115 produced by the exhaust steam, or under conditions when steam is not being used, as when the locomotive is coasting or running without steam power, the damper 16 controlling the draft passage 19 may be 120 opened so that a draft through the stack is produced by the onward movement of the locomotive. Thus, it is unnecessary to use steam merely for the purpose of producing the draft through the stack, and 125 130

hence, economy in the operation of the boiler is secured. It will be seen that by my horizontally extending stack and with the circuitous route of the products of combustion therethrough, ample opportunity is afforded for extinguishing sparks; for capturing, or saving combustible products of combustion which may be utilized by being again passed to the firebox; back pressure in the exhaust pipe, or tube 10 is prevented and the escape of cinders is prevented and they are conveyed to the ashpan where they can be conveniently disposed of. The exhaust from the pipe, or tube 10 after being directed down-
ward and rearward by the curved front plate 15 of the front chamber 21, splits or divides so that half, or substantially half of the current produced passes rearward on either side of the boiler and a large portion thereof enters and passes through the pipe 34 and is conveyed to the ashpan, while the remainder on each side of the boiler travels rearward and upward to the rear end of the intermediate chamber and thence passes forward, and, as has been explained, enters the third or last chamber from which the current or draft makes its exit, and being directed upward and rearward, avoids the envelopment of the engine and cars by es-
caping heat and gases when passing through contracted spaces, such as under bridges and through tunnels. The envelopment of the boiler by the stack in itself diminishes loss of heat by radiation from the boiler and the boiler also gets the benefit of the high temperature of the contents of the stack.

An important advantage from the use of the pipes leading from the spark arrester, or stack to the ash pit is that the hot gases, sparks, cinders and other unconsumed matters passing through and discharging from said pipes will mingle, or mix with the air entering the ash pan through the usual openings and will heat or raise the temperature of that air before it enters the fire, thus avoiding the chilling effect of admission of cold air to the fire box and the admixture of air with the combustible matter coming from the pipes promotes their combustion. By means of the dampers 35 in the spark pipes 34 the draft through those pipes into the ash pan may be regulated and any desired amount of gases and exhaust steam may be admitted to the ash pan. The dampers 35 are preferably operated from the cab.

It will be observed that by running the pipes 34 into the ash pan, I penetrate but a single wall, whereas, entry of the pipe into the fire box would involve penetrating two walls and passing through the water space with the necessity of a special construction that would protect against leakage of the water in the boiler. As will be seen by reference to the drawings, and in particular

to Fig. 1, it will be seen that the discharge end of the pipe 34 is below the mud frame and below the outside boiler shell. Besides the structural advantages of my construction it will be seen that the unconsumed combustible matters that are discharged from the pipes 34 reach the ash pan at a point where the most efficient mingling thereof with the air entering the ash pan is effected to the end that their combustion is promoted and the incoming air is warmed before it passes through the grates into the fire.

Having thus described my invention what I claim is—

1. A boiler having an outlet or stack arranged horizontally on the top with its discharge end at the rear and communicating directly to the atmosphere at the rear, a horizontal passage extending from the front end of the stack where it opens directly forward and reaching partially through the stack, through which passage air may be directly passed from the front of the stack, and a damper for controlling the movement of air through said passage.

2. The combination of a boiler having an outlet at its front end, and a stack upon the upper side of the boiler reaching from said outlet rearward and having a discharge opening leading directly to the atmosphere at its rear end, said stack having a downwardly and rearwardly extending plate that forms with the contiguous bottom of the stack, a contracted outlet, and a chamber into which said outlet discharges having an outlet above said plate.

3. The combination of a boiler having an outlet at its front end, and a stack upon the upper side of the boiler reaching from said outlet rearward and having a discharge opening leading directly to the atmosphere at its rear end, said stack having a downwardly and rearwardly extending plate that forms with the contiguous bottom of the stack a contracted outlet, and a chamber into which said outlet discharges having an outlet above said plate, and a horizontally extending passage above said plate leading from the front of the stack to take air and to pass it rearward into the stack.

4. The combination of a boiler having an outlet at its front end, a stack comprising a successive series of chambers and extending rearward on the outside of the boiler with a discharge opening at its rear end, and a controllable air passage leading into the stack at a point in rear of the front thereof.

5. The combination of a boiler having an outlet at its front end, a stack comprising a successive series of chambers and extending rearward on the outside of the boiler with a discharge opening at its rear end, and a controllable pressure-relieving passage between one of said chambers and another.

6. The combination of a boiler having an outlet at its front end, a steam exhaust communicating with said outlet, and a stack leading rearward on the outside of the boiler from said outlet and comprising a series of successive chambers, the last one of which has a discharge at the rear of the stack that opens directly to the atmosphere external to the boiler.
10. 7. A spark arrester having a front chamber, a chamber in rear thereof and a stack chamber and provided with means for delivering sparks or cinders to a receptacle and with an air inlet pipe.
15. 8. A boiler having a spark arrester arranged thereon, the spark arrester comprising a front chamber, a stack chamber, a chamber intermediate the stack chamber and front chamber, a pressure relief pipe leading from the intermediate chamber and the stack chamber and a valve or damper controlling the same.
20. 9. A spark arrester having an air inlet pipe for creating a draft therein and means controlling said air inlet pipe, substantially as set forth, the spark arrester having a pipe leading from the lower chamber to the top

chamber for increasing the draft through the top chamber and for relieving pressure in the lower chamber.

10. The combination of a boiler having an outlet at its front end, and a stack comprising a chamber in communication with said outlet at its front end and extending rearward therefrom and having an outlet at its rear end, said chamber and the portion of the stack rearwardly thereof being carried downward over each side of the boiler.

11. The combination of a boiler having an outlet at its front end, and a stack comprising a forward chamber in communication with said outlet at its front end and having a downwardly and rearwardly extending top wall that terminates in a chamber outlet, said chamber and the portion of the stack in rear of said outlet being carried downward over each side of the boiler.

In testimony that I claim the foregoing I have hereunto set my hand.

CHARLES W. CROWELL.
